[57] CLAIM

The ornamental design for a table, as shown and described.

DESCRIPTION

FIG. 1 is a front perspective view of a table showing my new design incorporated therein;

FIG. 2 is a rear elevational view of the table showing my new design; and

FIG. 3 is an end elevational view of the table showing my new design.

The ends and sides of the table, not shown, are mirror images of the respective ends and sides shown.

FIG-1

FIG-2

FIG-3
